E. L'Hommedieu.

Rolling Die.

Patented Apr. 28, 1830.

Ogden, D. Commissary
Letters Patent.

The Machine referred to in these Letters Patent and making part of the same containing a description in the words of the said Ogden D. Commissary himself of his improvement in the machine for shaping Hammer Spike Gimblets and Rod Augers.

The machine of which I claim the invention is constructed of iron in the following manner (viz.) The frame or clamp consists of four rectangular pieces of cast iron of about two inches in thickness, by eight inches wide, and the sides or upright pieces are about three feet long with notches near their ends, to receive the tenons of the cross pieces, which are about four inches long between joints. The frame should be firmly keyed together leaving the inside quadrangular about six by ten inches in the clear. On this frame is placed two cast iron Rolls about four inches thick and about eleven inches diameter, with necks or bearing extending through the side pieces in which they turn. Three of these necks are three inches diameter, and two of them extend without the frame about four inches to receive spur wheels by which the leading roll is turned by the driving roll. One neck upon the lower roll opposite the cog wheel side should be about four inches in diameter and made to receive a socket or coupling box to couple it to the driving shaft by which it may be put in motion. Upon the eyes or periphery of the lower or driving roll is made a groove about half an inch deep, in which is mounted a proper die to shape one side of the hammer. Gimblet or Auger as may be wanted, and upon the edge of the other roll is raised a tongue or list projecting about half an inch in which is inserted a proper die to shape the other side of the implement wanted as required. These rolls must be of equal diameter at their working parts and the tongue of one must fit the groove of the other, and the spur wheels by which they are connected must be of one pattern or diameter, that they may move together without slipping. This machine may be put in motion by any adequate power being applied to the driving shaft which is coupled to the driving roll, and the dies must

54455
be placed in the vise, and the opposite end and other which will
shape a piece of hot iron, steel, or other material to them into the
form desired. By this machine much time and labor may be saved
in shaping the above mentioned articles. I claim that the
application of the above described machine to the sharpening the articles of
said is my discovery, and for which I shall claim a Letters Patent.

For a further illustration of the machine refer to the drawing accom-
panying this Specification. For testimony whereof I have hereunto
set my hand and seal this 21st day of February A.D. 1830.
